ATTORNEYS.

UNITED STATES PATENT OFFICE.

WILLIAM J. RANKINS, OF AUGUSTA, KENTUCKY.

FENDER-SPAR.

SPECIFICATION forming part of Letters Patent No. 379,329, dated March 13, 1888.

Application filed January 13, 1888. Serial No. 260,588. (No model.)

To all whom it may concern:

Be it known that I, WILLIAM J. RANKINS, of 5
Augusta, in the county of Bracken and State
of Kentucky, have invented a new and Im-
proved Fender-Spar, of which the following
is a full, clear, and exact description.

My invention relates to an improvement in
fender-spars adapted for use on steamboats,
wharfs, and flat and ferry boats, and has for its
10 object to provide a device unaffected by the rise
and fall of the tide or the action of ice in the
river, and which will obviate the severe jar at
present consequent upon boats making a land-
ing either at the wharf or at wharf-boats, and
15 wherein, if the boat should by any means be
forced nearer the dock than originally in-
tended when the motive power is removed,
the boat will automatically be returned to its
original position.

20 The invention consists in the construction
and combination of the several parts, as will
be hereinafter fully set forth, and pointed out
in the claims.

Reference is to be had to the accompanying
25 drawings, forming a part of this specification,
in which similar letters of reference indicate
corresponding parts in all the figures.

Figure 1 illustrates one application of my
fender-spar. Fig. 2 is a side elevation of the
30 spar partly in section, and Fig. 3 is a trans-
verse section on line $x-x$ of Fig. 2.

In carrying out the invention, A represents
a spar provided with an extended longitudinal
bore, a, at the inner end, in which a spring, a',
35 is coiled, and a shorter longitudinal bore, a'',
at the outer end.

In the under side of the spar a longitudinal
slot, B, is cut intersecting the bore a, and ex-
tending from the inner end of the spar out-
40 ward nearly the length of said bore, as shown
in Fig. 2.

Against the inner end of the spring a' a cir-
cular plate, b, is made to bear, which plate is
engaged by the head d of a pin, D, the inward
45 movement of the said pin-head being limited
by a plug, D', entered the inner end of the
spar, and the plug is retained in position and
the spar strengthened by a thimble, D'', through
which ferrule, plug, and spar a pin or screw or

equivalent fastening device is passed, as illus- 50
trated in Fig. 2.

In the bore a'' at the outer end the shank of
a bifurcated head-block, E, is entered to turn
therein, being provided to that end with an
annular groove, e, in the shank adapted to re- 55
ceive a pin, e', inserted in the spar. One sur-
face of the head-block is decidedly convex and
the opposing surface slightly concave, where-
by a claw-like appearance is imparted thereto.
At a point upon the upper surface of the spar 60
an eye, e'', is attached or inserted, to which a
tackle, H, is secured leading inboard to any
desired point.

In operation a bracket, H', is attached to
the wharf or the gunwale of a boat, and in said 65
bracket the projecting end of the pin D is
socketed. Thus, if attached to a boat, by al-
lowing the bifurcated end to drop down to the
bottom the boat may be held steady for repairs
or painting or kept a given distance off shore, 70
or the spar, as illustrated, may be employed
to ease the approach of a vessel to a dock or
be utilized to keep the same a given distance
from the same when loading, unloading, or
simply tied up. 75

The head-block is made reversible in order
that the claws may be reversed to accommo-
date the spar to the rising or falling of the tide
or river.

Having thus described my invention, what 80
I claim as new, and desire to secure by Letters
Patent, is—

1. A spar provided at its inner end with a
pivot having a sliding and yielding connection
therewith, and at its outer end with a head- 85
block, substantially as described.

2. A spar provided at its inner end with a
pivot having a sliding and yielding connection
therewith, and at its outer end with a revers- 90
ible bifurcated head-block, substantially as de-
scribed.

3. In a fender-spar, the combination, with
a slotted tubular body, a spring held in one
end thereof, and a reversible head-block sup- 95
ported in the opposing end, of a headed pin
engaging the said spring and a bracket adapted
as a socket for the pin, substantially as shown
and described, and for the purpose set forth.

4. In a fender-spar, the combination, with a slotted tubular body, a spring held in the inner end thereof, a plate to the rear of said spring, and a reversible bifurcated head-block
5 in the outer end, of a headed pin engaging the said plate and bearing upon the spring, a bracket adapted as a socket for said pin, and

means, substantially as shown and described, for raising and lowering the spar, as and for the purpose herein set forth.

WILLIAM J. RANKINS.
